(57) **CLAIM**

The ornamental design for a currency processing machine, as shown and described.

DESCRIPTION

FIG. 1 is a front view of a first embodiment of a currency processing machine showing my new design;

FIG. 2 is a rear view thereof;

FIG. 3 is a left side view thereof;

FIG. 4 is a top plan view thereof;

FIG. 5 is a bottom view thereof;

FIG. 6 is an upper right front perspective view thereof;

FIG. 7 is a front view of a second embodiment of a currency processing machine showing my new design;

FIG. 8 is a rear view thereof;

FIG. 9 is a left side view thereof;

FIG. 10 is a top plan view thereof;

FIG. 11 is a bottom view thereof;

FIG. 12 is an upper left front perspective view thereof;

FIG. 13 is a front view of a third embodiment of a currency processing machine showing my new design;

FIG. 14 is a rear view thereof;

FIG. 15 is a top plan view thereof;

FIG. 16 is an upper left front perspective view thereof;

FIG. 17 is a front view of a fourth embodiment of a currency processing machine showing my new design;

FIG. 18 is a rear view thereof;

FIG. 19 is a top plan view thereof;

FIG. 20 is an upper left front perspective view thereof;

FIG. 21 is a top plan view of a fifth embodiment of a currency processing machine showing my new design;

FIG. 22 is a top plan view of sixth embodiment of a currency processing machine showing my new design;

FIG. 23 is a top plan view of a seventh embodiment of a currency processing machine showing my new design;

FIG. 24 is a top plan view of an eighth embodiment of a currency processing machine showing my new design;

FIG. 25 is a top plan view of a ninth embodiment of a currency processing machine showing my new design; and,

FIG. 26 is a top plan view of a tenth embodiment of a currency processing machine showing my new design.

In each embodiment, a right side view is omitted because the right side view is symmetrical to the left side view.

In each of the third embodiment and the fourth embodiment, a left side view and a bottom view are omitted because they are identical to the respective views in the second embodiment.

In each of the fifth embodiment to the tenth embodiment, a front view, a rear view, a left side view and a bottom view are omitted because they are identical to the respective views in the fourth embodiment.

The broken lines in drawings depict portions of the currency processing machine that forms no part of the claimed design.
